UNITED STATES PATENT OFFICE.

CHARLES W. RAINKE, OF BROOKLYN, NEW YORK.

ILLUMINATED REFLECTING-SIGN.

1,390,459.

Specification of Letters Patent. Patented Sept. 13, 1921.

Application filed June 30, 1921. Serial No. 481,574.

To all whom it may concern:

Be it known that I, CHARLES W. RAINKE, a citizen of the United States, residing at Brooklyn, in the county of Kings and State of New York, have invented certain new and useful Improvements in Illuminated Reflecting-Signs, of which the following is a specification.

The main object of this invention is the provision of signs, and letters and other characters for signs, illuminated by a plurality of reflecting elements, receiving light from one or more lamps.

Another object is the provision of a particularly designed reflecting element for efficiently and intensely reflecting the light so as to produce the same effect upon a spectator as would a lamp.

Another object is the provision of novel and efficient means and combinations of parts for mounting said reflectors and lamps, so as to make the same most effective and efficient, as well as practical and sufficiently inexpensive to enable the same to be sold at a reasonable cost on the market.

The above and other objects will become apparent in the description below, in which like-named characters of reference refer to like-named parts in the drawings.

Referring briefly to the drawings, Figure 1 is a front elevational view of a complete letter made in accordance with my invention.

Fig. 2 is a cross-sectional view of the same on the line 2—2 of Fig. 1.

Fig. 3 is an enlarged, central longitudinal cross-sectional view, in elevation, of one of the reflector elements, showing also the means of mounting the same.

Fig. 4 is an underside plan view of the portion of the sign or letter shown in Fig. 3.

Fig. 5 is an enlarged view, partly in section, showing one of the illuminated lamps and the means which I provide thereon to enhance the efficiency of my device.

Fig. 6 is an end view of the lamp shown in Fig. 5.

Fig. 7 is a perspective view of a portion of the mounting frame of my device, showing the means for securing a reflector element therein.

Fig. 8 is a fragmentary perspective view of the mica shield which may be wrapped around the lamp in a manner which will become apparent, for the purpose which

will also become apparent, in the following description.

Referring briefly to the drawings, the numeral 1 represents a rectangular frame having a sheet of rigid, preferably metallic, material inclosing the same, shown at 2. The form 3 of a letter is inclosed by walls 6 extending normally from the surface 2, said form being provided with a series of spaced apart reflector elements generally represented at 4. The walls 6 rise to a height from the surface 2 slightly greater than the height of the reflectors 4 above said surface, and the sides of said walls are preferably black, as is also the surface 7 inclosed by the letter 3. The surface 8 between the letter 3 and the frame 1 may be of any color or shade desired.

The reflector element 4 constitutes a substantially cylindrical, hollow glass body 75 having a portion of its surface formed at an inclination to the axis of the body, shown at 9, said surface being substantially elliptically convex, and being well represented as a "belly." The body of the element 4 extends in a ridge or edge 11 around said belly, leaving a slight groove 10 about the periphery of the belly. A stem 12, also hollow, extends from the body 4. The entire interior of the body 4 and stem 12 is silvered 80 or otherwise treated to cause the exterior surface of the element to act as a reflector.

A cap 13 fits about the stem 12, both the exterior surface of said stem and the cylindrical portion of said cap, being screw 90 threaded. In assembling the reflectors, a cement or other binder is used so that, once the cap is in position about the stem, it remains there permanently, and provides a permanent, air-tight closure for the body of 95 the element, thus preventing injury or loss of perfection on the reflecting surface of the element.

For mounting the reflector elements, portions of the material 2 are cut away so as to provide an opening 16 of the form shown. The material thus cut away is bent back at right angles to the member 2, so as to form a shank or tongue 15 possessing resiliency. The edge 17 of the opening 16, directly opposite the tongue 15, is of a curvature having a larger diameter than the curvature of the cap 13, as shown by the dotted line 17 in Fig. 4. By this provision, the stem 12 may be screwed into the opening 16, for the edge 110

17 will act as a portion of a thread and will engage the threads 14 of said stem. At the same time the force of the resilient tongue 15 urging against the side of said stem will 5 tend to force the latter toward the edge 17 so as to cause engagement of the threads 14 with said edge 17.

The illuminating lamp 18 is situated centrally of the letter 3, the same being 10 visible in Fig. 1 under the cover 24. When colored light is desired, a shield 19 of mica or other transparent material of the color desired is formed of a single sheet having the ends joined at 20, and is wedged upon 15 the tapered surface of the lamp so as to hold the same securely. If colored light is not desired, said shield is omitted.

The usual lamp shade socket, comprised of two clamp-like members 21 and 22, may 20 be used for the lamp. I provide a special shade 23 secured between said members as shown, said shade extending partway along the length of the lamp 18, and being black or darkened on the surface. A cover 24 of 25 substantially the form of a bell, having a plurality of spaced apart spring clips or tongues 25 cut out therefrom, is provided over the end of the lamp 18, and extends about said lamp over about one-half of the 30 length of the latter. Thus there is provided a space between the shade 23 and cover 24 through which a band of light may pass from the lamp.

When the whole letter or sign is set up, 35 all of the reflecting elements 4 are so placed that an imaginary plane passing radially from the axis of the lamp to the axis of the reflector, would divide the belly 9 in two equal parts. The light radiating from the 40 light band or belt just mentioned then strikes the reflectors and the inclined surfaces thereof reflect the light in a direction substantially at right angles to the frame 1.

However, the provision of the belly 9 causes the latter to appear as a separate, intensely 45 illuminated, source of light. The actual source of light is concealed by the cover 24. The inside surface 7 of the letter frame is black and therefore does not interfere with the definiteness of the outline of the letter. 50 The outer wall 6 prevents any of the direct light from striking the surface 8, so that the outline of the letter is not interfered with.

The whole device as described truly represents a sign or other attractive contrivance 55 composed of lamps instead of reflectors, and the effect is so pronounced that the uninitiated observer would believe that the elements forming the letter are lamps.

I claim:

1. A device of the class described comprising a frame, a wall rising from said frame and inclosing the form of a letter or the like, a plurality of spaced apart reflector elements mounted on said frame within said wall, said wall extending to a distance from said frame slightly greater than the height of said elements above said frame, a source of light situated substantially centrally of said letter or the like, and means on said source of light 70 for preventing issuance of light therefrom excepting in a band extending partway between the ends of the axis of said source of light.

2. A reflecting element comprising a substantially cylindrical hollow body having an inclined surface, said surface being provided with an outwardly extending belly, a groove surrounding said belly, a ridge surrounding said groove, a hollow stem extending from said body, a cap sealed upon said stem, said cap being provided with means for mounting said reflecting element.

In witness whereof I affix my signature.

CHARLES W. RAINKE.
